Primary Examiner — Karen S Acker

Assistant Examiner — Andrea Marie McKay

(57) **CLAIM**

The ornamental design for a flip barbecue grill, as shown and described.

DESCRIPTION

7. Flip barbecue grill

7.1 : Perspective

7.2 : Perspective

7.3 : Front

7.4 : Back

7.5 : Left

7.6 : Right

7.7 : Top

7.8 : Bottom

7.9 : Enlarged

7.10 : Enlarged

The evenly spaced broken lines depict portions of the flip barbecue grill that form no part of the claim. The dash-dot-

(Continued)

dash broken lines denote the boundaries of the areas of detail
and form no part of the claimed design.

1 Claim, 10 Drawing Sheets
